MATERNITY FROCK

Jeanette Mott, Minneapolis, Minn.

Application February 26, 1940, Serial No. 320,914

5 Claims. (Cl. 2—76)

An object of this invention is to provide a frock which can be worn throughout a period of pregnancy; which is relatively slender at the start and which can be let out from time to time to accommodate the figure of the wearer as it bulges outwardly and downwardly while the entire skirt portion including the hem remains substantially in the initial position, thereby combining a stylish and neat appearance with comfort to the last.

10 This is accomplished by having the skirt and bodice portions secured together at the back and partly around the sides, preferably with an intermediate front or apron section therebetween, the upper portion of the apron section and the lower 15 portion of the bodice having means such as plaits, preferably at the sides, which at first are closed by snap fasteners or the like and which can be let out, one at a time, as desired, to accommodate the apron portion or front to the bulging figure. For 20 the same reason, the fronts of the skirt and bodice portions are secured only by means of a bib front extending upwardly, from the middle of the apron portion and having separable fasteners by means of which it can be secured to any one of a number 25 of complementary fasteners on the bodice. The whole provides a front which is nearly straight at first but which gives a more and more roundly "bagging" effect which at all stages naturally and comfortably fits the bulging abdomen of the 30 wearer and which is greatly aided by the roundly dipping front line of the bottom of the apron portion.

These and other objects, as will hereinafter appear, are accomplished by the invention which 35 is fully described in the following specification and shown in the accompanying drawing in which

Figure 1 is a nearly front view of a figure wearing a frock embodying the invention;

Fig. 2 is a side elevation of the same; and

40 Fig. 3 is a detailed view of the side plaits showing them partly open.

The frock shown is without overblouse which may be of any style to suit the existing fashion but has simple straight sides which have a series 45 of vertical sewed-in concealed plaits under the arm and extending out along the under side of the arm which may be opened from the bottom as needed to give the necessary room.

The frock illustrated, preferably comprises a 50 bodice 10, a front or apron portion 11 and a skirt 12, the latter two being sewed together by a seam 13 which preferably starts near the hip on each side and dips in front for a purpose later to be explained. The bodice and apron portions are 55 secured together by a line of stitching 14 across

the back which ends at a side point 14a, leaving the front of these portions unsecured to each other except by a bib 15 which preferably has one element of spaced separable fasteners 16 secured thereto and adapted to engage any pair of complementary elements 17, 18 or 19 on the bodice to meet the needs of the wearer as will later be seen. The bodice preferably opens at the front line 10a and is secured as by separable fasteners not shown. This apron front is worn up as shown in Fig. 1 in full lines, but may be turned down as shown in dotted lines to fasten the front of the bodice.

A side plait 20 is provided at each side of the apron section and is shown in detail in Fig. 3. It is worn closed at first and is held in place by snap fasteners or the like 21, 22 on meeting surfaces. A similar plait 23 at each side provide additional fullness when needed.

The lower portion of the bodice is also provided 20 with V-shaped plaits 24, 25 at each side and are also secured as by means of separable fasteners as 26, 27.

When some or all of these side and V-shaped 25 plaits are released and the fasteners 16 within the bib are secured to corresponding fasteners 18 or 19 the apron "bags" into the dotted line of position Fig. 2, largely because the lower edge of the apron portion 11 is firmly secured to the skirt by the seam 13, while the middle portion is given 30 roundness by opening the V-shaped plaits 20, 23, 24 and 25 at each side. To accomplish this bagging effect, particularly in the vertical plane, it is necessary that the top of the bib be dropped and this is accomplished by means of the pairs 35 of spaced fasteners 17, 18, 19. The effect of all this is to provide a front to the frock which accommodates itself naturally and easily to the wearer at all stages and provides a frock which is both neat and comfortable.

The several plaits may, if desired, be secured by stitching instead of separable fasteners, but this is not so desirable for the reason that the latter can be opened for putting the frock on or taking it off. The wide girth of the skirt at the 45 hips when these are unfastened enables the user to step into the frock or out of it thereby obviating the necessity for stretching her arms over her head as is required by many frocks in putting them on or taking them off. This feature is 50 highly regarded by obstetricians.

The spaces under the armpits are preferably left open for greater comfort and freedom of movement. This space is then covered by the overblouse which has previously been described. 55

It will also be apparent that I may use only the fasteners 16, 17 and insert horizontal plaits in the upper part of the bib (not shown) which can be ripped, one at a time, to add additional length to the bib to provide the bulging in the vertical plane.

While I have shown and described a few embodiments of the invention, it will be understood that it is capable of many modifications. 10 Changes, therefore, in the construction and arrangement may be made which do not depart from the spirit and scope of the invention as disclosed in the appended claims.

I claim as my invention:

- 15 1. In a garment of the class described, a bodice, a skirt secured to the bodice across the back and along the sides so as to support the entire skirt and having its front cut away below the waist line forming a remaining front skirt part with its upper edge below the waist line, and an apron sewed at its bottom to said upper edge of the skirt, means on the apron for permitting circumferential expansion of the apron in a horizontal plane, and means for adjustably securing the apron to the bodice at any one of a plurality of heights to permit expansion in the vertical plane.
- 20 2. In a garment of the class described, a bodice, a skirt secured to the bodice across the back and along the sides so as to support the entire skirt and having its front cut away below the waist line forming a remaining front skirt part with its upper edge below the waist line, and an apron sewed at its bottom to said upper edge of the skirt, means on the apron for permitting circumferential expansion of the apron in a horizontal plane, and means for adjustably securing the apron to the bodice at any one of a plurality of heights to permit expansion in the vertical plane.
- 25 3. In a garment of the class described, a bodice, a skirt secured to the bodice across the back and having its front cut away below the waist line forming a remaining front skirt part with its upper edge below the waist line, and an apron sewed at its bottom to said upper edge of the skirt, the apron having a bib, means on the apron for permitting circumferential expansion of the apron in a horizontal plane, and means for adjustably securing the bib to the bodice at any one of a plurality of heights to permit expansion in the vertical plane.
- 30 4. In a garment of the class described, a bodice, a skirt secured to the bodice across the back and along the sides so as to support the entire skirt and having its front cut away below the waist line forming a remaining front skirt part with its upper edge below the waist line, and an apron sewed at its bottom to said upper edge of the skirt, means on the apron for permitting circumferential expansion of the apron in a horizontal plane, and means for adjustably securing the apron to the bodice at any one of a plurality of heights to permit expansion in the vertical plane.
- 35 5. In a garment of the class described, a bodice, a skirt secured to the bodice across the back and along the sides so as to support the entire skirt and having its front cut away below the waist line forming a remaining front skirt part with its upper edge below the waist line, and an apron sewed at its bottom to said upper edge of the skirt, the apron having a bib, plaits in the sides of the bodice and in the sides of the apron and separable fasteners in said plaits for permitting circumferential expansion of the apron in a horizontal plane, and means for adjustably securing the bib to the bodice at any one of a plurality of heights to permit expansion in the vertical plane.

along the sides so as to support the entire skirt and having its front cut away below the waist line on a line extending downwardly and forwardly from each hip forming a remaining front skirt part with its upper edge below the waist line, and an apron sewed at its bottom to said upper edge of the skirt, means on the apron for permitting circumferential expansion of the apron in a horizontal plane, and means for adjustably securing the apron to the bodice at any one of a plurality of heights to permit expansion in the vertical plane.

4. In a garment of the class described, a bodice, a skirt secured to the bodice across the back and along the sides so as to support the entire skirt and having its front cut away below the waist line on a curving line forming a front skirt portion with a concave upper edge below the waist line, and an apron having a rounded bottom sewed at its bottom to said concave upper edge of the skirt, means on the apron for permitting circumferential expansion of the apron in a horizontal plane, and means for adjustably securing the apron to the bodice at any one of a plurality of heights to permit expansion in the vertical plane.

5. In a garment of the class described, a bodice, a skirt secured to the bodice across the back and along the sides so as to support the entire skirt and having its front cut away below the waist line forming a remaining front skirt part with its upper edge below the waist line, and an apron sewed at its bottom to said upper edge of the skirt, the apron having a bib, plaits in the sides of the bodice and in the sides of the apron and separable fasteners in said plaits for permitting circumferential expansion of the apron in a horizontal plane, and means for adjustably securing the bib to the bodice at any one of a plurality of heights to permit expansion in the vertical plane.

JEANETTE MOTT.
